GAS BURNER

Carroll Cone, Lucas County, Ohio, assignor to
Surface Combustion Corporation, Toledo, Ohio,
a corporation of New York

Application May 1, 1933, Serial No. 668,733

6 Claims. (Cl. 158—110)

In heating operations conducted in a fuel fired furnace, it is sometimes desirable to produce a relatively long flame and at other times a relatively short flame. The present invention, therefore, has for its object to provide a gas burner capable of being operated to produce a relatively long luminous flame and also capable of being operated to produce a relatively short spreading flame and withal to provide a burner which shall be simple in construction and well adapted for its intended purpose.

The various features of novelty and invention will fully appear from the detailed description taken in connection with the accompanying drawing forming part of this specification and wherein,—

Fig. 1 is a longitudinal section through the improved burner, a portion of the wall of the furnace to be fired being also shown;

20 Fig. 2 is a section on line 2—2 of Fig. 1, and Fig. 3 is a section on line 3—3 of Fig. 1.

In the drawing, numeral 10 indicates a portion of a furnace wall which is apertured to receive a refractory body or tunnel 11. At one end of the 25 tunnel is a chambered casing generally indicated at 12. At one side of this casing is an annular flange 13 whereinto one end of the tunnel 11 projects. The casing 12 is provided with an air chamber 14, the inlet to which is indicated at 15, 30 and a gas chamber 16, the inlet to which is indicated at 17. These two chambers are separated from each other by a common partition wall 18 having a relatively large circular aperture 19 coaxial with that of the flange 13.

35 Secured to the wall 18 and projecting therefrom into the tunnel 11 in radially spaced relation is a refractory tube, generally indicated at 20. For securing the tube to the wall 18, there is provided on the tube a radial flange 21 which is clamped between said wall and a clamping ring 22 by means of bolts 23 secured in the wall 18. On the outside of the tube 20 are longitudinally extending ribs 24 for maintaining the tube and tunnel in spaced concentric relation. The annular 45 passage 25 thus formed between the inner wall of the tunnel and the outer wall of the tube 20 is in direct communication with the air chamber 14.

Concentrically positioned within the tube 20 in radially spaced relation to form an annular passage 38 and projecting therefrom is a refractory 50 tube 26. Internal longitudinally extending ribs 24 on the tube 20 maintain the tubes 20 and 26 in radially spaced relation. The tube 26 is secured to an annular wall section 27 as by means of bolts 28 secured to said section and a ring 29 be-

tween which and said wall section a flange on the tube 26 is clamped. The annular wall section 27 is part of a chambered structure 30 which is removably secured to the outer face of the casing 12 as by means of bolts 31. It will be understood that when the structure 30 is disconnected from the casing 12, the tube 26 will be withdrawn from the tube 20. The annular passage 38 is in direct communication with the gas chamber 16.

The chamber of the structure 30 is indicated at 32 and this chamber and the air chamber 14 are in direct communication by way of a passage 33 in the form of a relatively wide slot as clearly shown in Fig. 2. From this it will be understood that the chamber 14 is in direct connection with the interior of the tube 26. As already stated the chamber 14 is also in direct communication with the annular passage 25 between the tunnel 11 and the tube 20.

Positioned within the chamber 32 is an air deflector or vane 34 affixed to a shaft 35 having a crank arm 36 arranged in abutting relation with an arcuate locking flange 37 on the face of the structure 30. When the vane is in the position indicated by the broken lines in Fig. 2 the air flowing through the passage 33 from the chamber 14 will be deflected toward the right as viewed in Fig. 2 and hence the air will tend to flow as indicated by the arrows in Fig. 2, that is to say, in a clockwise direction with the result that the air will enter the tube 26 with a rotary motion.

When the vane 34 is vertically disposed as shown in Fig. 2 it will, of course, have no particular effect on the air flowing through the passage 33 and hence the air will enter and flow through the tube 26 without rotary motion. The vane may be locked by the crank arm 36 at any degree of angularity within its limits of movement and hence the degree of rotation of the air entering the tube 26 can be readily controlled as will now be readily appreciated.

The air and gas will ordinarily be supplied to their respective chambers 14 and 16 at relatively low and preferably equal pressures. When the vane 34 is in vertical position as indicated in full lines in Fig. 2, the air and gas will flow from the tunnel 11 as a composite stream made up of well defined streams of air and gas. In such composite stream, mixing of the air and gas takes place primarily by interdiffusion with the resultant production of a luminous flame of substantial length. On the other hand it is possible, without disturbing the governing apparatus (not shown) which controls the admission of air and gas to the burner, to cause a more rapid mixing of the

air and gas by the simple expedient of so adjusting the vane 34 that rotary motion will be imparted to the air flowing into the tube 26. Upon leaving the tunnel the mixture tends to spread out radially and hence there is produced a relatively short spreading flame as will now be readily understood.

The ribs 24 and 24' materially assist in causing the air and gas to leave their passages 25 and 38 in stream line flow as will be readily appreciated.

What I claim is:—

1. A gas burner comprising in combination, a casing provided with pressure air and gas supply chambers respectively, a tunnel associated with the casing and receiving air from the air supply chamber, a pair of radially spaced concentric tubes within and projecting from said tunnel, said air supply chamber being in communication with the inner tube and the gas supply chamber with the outer tube, the outer tube being radially spaced from the walls of the tunnel.

2. A gas burner comprising in combination, a casing provided with pressure air and gas supply chambers respectively, a tunnel associated with the casing and receiving air from the air supply chamber, a pair of radially spaced concentric tubes within and projecting from said tunnel, said air supply chamber being in communication with the inner tube and the gas supply chamber with the outer tube, the outer tube being radially spaced from the walls of the tunnel, and means between the inner tube and its communicating chamber for causing the air from such chamber to enter the tube with a rotary motion.

3. In the combination specified in claim 2, said means comprising an adjustably mounted vane disposed in the path of flow of the air.

4. In the combination specified in claim 1, said inner tube projecting from the tunnel to a greater extent than the outer tube, and the gas chamber surrounding the projecting end of the inner tube.

5. A gas burner comprising in combination, a casing provided with pressure air and gas supply chambers respectively, a tunnel associated with the casing and receiving air from the air supply chamber, a pair of radially spaced concentric tubes within and projecting from said tunnel, said air supply chamber being in communication with the inner tube and the gas supply chamber with the outer tube, the outer tube being radially spaced from the walls of the tunnel, and circumferentially spaced means dividing the annular spaces formed by said tubes into individual straightaway passages.

6. In a gas burner, the combination of an air chamber divided into two communicating compartments by a wall having a slot, a combustion tunnel in communication with one of said compartments, a tube in communication with the other compartment and projecting into said tunnel, a vane in that compartment which is in communication with said tube, means for turnably supporting said vane at one side of the axis of said tube, said vane being adapted to be moved into a position which is tangent to the said tube whereby to impart rotary motion to the air entering the same, a second tube within and projecting from said tunnel and surrounding the first tube in spaced relation and a gas chamber in communication with the second tube.
